DAVID P. DAVIES, OF RACINE, WISCONSIN, ASSIGNOR TO J. I. CASE THRESHING MACHINE COMPANY, OF RACINE, WISCONSIN, A CORPORATION.

INTERNAL-COMBUSTION ENGINE.

1,217,285.

Specification of Letters Patent. Patented Feb. 27, 1917.

Application filed May 25, 1912. Serial No. 699,780.

To all whom it may concern:

Be it known that I, DAVID P. DAVIES, a citizen of the United States, and a resident of Racine, county of Racine, and State of Wisconsin, have invented certain new and useful Improvements in Internal-Combustion Engines, of which the following is a full, clear, and exact description.

The invention relates to internal combustion engines and the invention consists in the features of improvement hereinafter set forth, illustrated in the accompanying drawings and more particularly pointed out in the appended claims.

In the drawings, Figure 1 is a plan view of the improved engine with the cover of the crank case removed and certain parts shown in section. Fig. 2 is a longitudinal section. Fig. 3 is a detail view of the governor controlled throttle valve. Fig. 4 is a cross-section on the line 4—4 of Fig. 2. Figs. 5 and 6 are detail sections on the lines 5—5 and 6—6, respectively of Fig. 1.

The drawings illustrate a two cylinder engine of the horizontal type, although it is to be understood that one or more cylinders can be employed and the engine vertically disposed, if desired. The engine cylinders 1 are provided with heads 2. The opposite, inner ends of the cylinders fit within openings in one end of the crank casing 3 and are provided with flanges 4 by which they are secured to the crank casing. Pistons 5 within the cylinders are connected by pitman rods 6 to the crank pins 7 of the engine shaft 8. The latter is journaled in suitable bearings 9 on the sides of the crank casing and on a longitudinally extending, U-shaped rib or partition which extends upwardly from the bottom of the crank casing midway between the sides thereof.

In the construction shown, the engine is horizontally disposed and the crank casing fits between a pair of supporting side bars 11, which may form the sills of a traction engine or the like. These side bars are preferably formed of steel channels, the crank casing of the engine being bolted thereto and having side flanges 12 which rest upon the upper flanges of the side bars. Each cylinder 1 is provided with a downwardly projecting portion 13 which forms the exhaust valve casing and which are provided with flattened, lower faces that rest upon the upper end of a transverse Z-bar 14 that ex-

tends between and is connected to the side sills or supports 11. The cylinders are not fixed to the transverse supporting bar 14, but are free to slide to a slight extent thereon as they are heated and cooled. 60

The depending cylinder portion 13 is provided with an exhaust passage 15, and the port leading thereto is controlled by an exhaust valve 16 on the inner end of a stem 17 which extends through a suitable guide-way or sleeve formed in the part 13. An inlet valve casing 18 is mounted on the head 2 of each cylinder and carries an inlet valve 19 on a stem 20. The inlet and exhaust valves are held to their seats by coiled springs 21 and the valves are operated by rockers 22 and 23 mounted within the crank casing between the cylinders and the engine shaft. The rockers 22 for operating the exhaust valves are mounted intermediate their ends upon a pivot shaft which extends through and is centrally fixed to a bracket 25. This bracket is mounted upon the central rib 10 of the crank casing and projects upwardly therefrom. Actuating rods 26, 80 connected to the lower ends of the rockers 22, extend through openings in the inner end face of the crank casing and engage the ends of the exhaust valve stems 17. The rockers 23 for operating the inlet valves are mounted intermediate their ends upon pivot shafts 27 that are secured to and project inwardly from the side walls of the crank casing 3. Actuating rods 28 are connected to the lower ends of the rockers 23 and extend rearwardly therefrom through openings in the end wall of the crank casing, and are each connected, at its rear end, to a rocker 29 which is pivoted intermediate its ends on a bracket 30. The bracket 30 is mounted on the corresponding inlet valve casing 18, and the end of the rocker is provided with a roller 29' arranged to engage the end of the inlet valve stem 20. 95

The valve actuating rockers 22 and 23 are operated from a cam shaft 31 which is arranged in the upper rear portion of the crank casing and is journaled at its ends in bearings 32, fixed to the side walls of the crank casing. Intermediate its ends, the cam shaft is journaled in a bearing 33 on the bracket 25. This shaft is driven, as usual, at half the speed of the engine shaft by a gear or pinion 34 on one end of the crank shaft, which is connected to a gear 35 on the 100 105 110

adjacent end of the cam shaft through the medium of an intermediate gear 36.

The inlet valve rockers 23 are operated by cams 37 fixed to the shaft 31 adjacent its ends and arranged to engage rollers 38 mounted on the upper ends of the rockers. The exhaust valve rockers 22 are operated by cams 39 fixed to the shaft and arranged to engage rollers 40 on the upper ends of the rockers. Each cam 39 is provided on one side with a comparatively long lug 41 which is substantially as wide as the body of the cam itself and which coöperates with its rocker 22 to hold the exhaust valve open during the exhaust stroke of the piston. At a diametrically opposite point, each cam 39 is provided with a short, narrow lug 42 which is normally out of line with the roller 40. These parts are, however, relatively shiftable, so that the roller 40 can be acted upon by both the lugs 41 and 42, and the latter is arranged to hold the exhaust valve open during a portion of the compression stroke. The parts are shifted to throw this narrow lug into operation when the engine is started by hand, so as to partially relieve the compression and thus facilitate the starting operation.

In the preferred construction shown, the rollers are laterally shiftable to a limited extent on pins 43, carried by the upper forked ends of the rockers 22. A bar or member 44 is arranged to slide in a direction parallel to the cam shaft 31 in guide-ways formed in a pair of lugs or blocks 45 on the bracket 25. A pair of blocks 46 are adjustably connected by set screws 47 to the ends of the sliding member or bar 44, and the under sides of these blocks are grooved to receive the rollers 40 and to form side flanges, which slightly overlap the edges of the rollers. The blocks 46 and the grooves therein are so arranged that they do not interfere with the movement of the rollers 40 and rockers 22 effected by the cams, but by shifting the member 44 and the blocks 46 thereon laterally, the rollers 40 can be moved into and out of line with the narrow lugs 42 of the cams. This shift is effected by a lever 48 pivoted between its ends on the bracket 25 and having a head on its upper end (see Fig. 3), which engages a notch in the sliding member or bar 44. The lower forked end of the lever 48 engages the eccentric pin 49 on the end of a shaft 50. This shaft extends outwardly from the crank casing toward the head end of the cylinders, and is journaled in a bracket 51 on the under side of the inlet or manifold pipe 52. A handle 53 serves to oscillate the shaft 50 and, through the medium of the bar 44 and grooved blocks 46 thereon, shift the rollers 40 into and out of line with the narrow lugs 42 on the exhaust cams. Ordinarily, of course, the rollers are held out of line with these lugs, but, can be

readily shifted into line therewith, when the engine is started, to hold the exhaust valves open during portions of the compression strokes.

The igniters, in the form shown, are of the make-and-break type. Plugs 54 are mounted at the upper portions of each head 2 and carry fixed and movable electrodes 55 and 56. The fixed electrode is carried on an insulated post 55', and the movable electrode upon a short rock shaft 56' extending through the plug. At its upper end, the shaft 56' is provided with an arm 57, the outer forked end of which engages an operating rod 58. The fixed electrode is shifted to engage the movable electrode by a sleeve 59 loosely mounted on the rod 58 and which is pressed into engagement with a recess in the side of the arm 57 by a spring 60. The spring 60 is coiled about the rod and extends between a shoulder on the sleeve 59 and a collar 61, which is adjustably fixed to the rod by a set screw 62. A hammer 63 for separating the electrodes, is adjustably threaded upon the outer end of the rod 58, and is held in place by a lock nut 64.

At its opposite end, the actuating rod extends through a guide sleeve 65 which extends through and is fixed to the end wall of the crank casing. The central portion of the bore of this sleeve is enlarged, and a spring 66 therein is coiled about the rod and engages a collar 67 thereon, and this spring tends to hold the actuating rod in such position that the electrodes are separate.

Each actuating rod 58 is operated from the cam 69 on the shaft 31, and preferably, through the medium of an adjustable tappet arm 70. The arms 70 are pivoted to the ends of rock arms 71 which are mounted upon the ends of a short rock shaft 72. The latter is journaled in an upwardly projecting portion 73 on the bearing 33 of the cam shaft and is provided intermediate its ends with a depending arm 74.

The tappet arm 70 hangs down from the arm 71 between the cam 69 and the igniter actuating rod 58, and abuts against the latter. An L-shaped dog 75 is pivoted upon the lower end of the tappet arm and is arranged to be engaged by the periphery of the cam 69. The latter is provided with an enlarged portion, terminating in an abrupt shoulder 76. As the cam rotates in the direction indicated by the arrow, the dog 75 is pressed thereby against the tappet arm 70, and the latter is shifted to move the igniter actuating rod 58. The movement of the latter compresses the springs 66 and 60 and presses the electrodes of the igniter firmly into contact. It also shifts the hammer 63 away from the arm 57 on the shaft of the movable electrode. When the dog 75 passes over the abrupt shoulder 76, the actuating rod is quickly restored by the spring 66 and the hammer 63.

strikes the arm 77 to quickly separate the electrodes.

The dog 75 is one-way acting. That is to say, it is yieldingly held in position by a 5 spring 77 attached thereto and bearing on the lower end of the tappet arm 70. If the engine starts in backward direction, the dog 75 will yield when the shoulder 76 of the cam strikes it and will not be broken. By adjusting the tappet arm and dog 75 thereon relatively to the cam 69, the time of ignition, relatively to the movement of the pistons, can be varied, as desired. This adjustment is effected by a rod 78 which extends through 15 the upper end portion of the crank casing and is connected to the arm 74 on the shaft 72. The forward end of this rod is connected to an arm 79 on a shaft 80. The latter is journaled in brackets 81 on the manifold pipe 20 52 and is provided at one end with an operating lever 83. This lever is provided with the usual dog or catch arranged to engage a segment 84 to hold the parts in adjusted position. By this means, the time of ignition 25 in the engine cylinders can be controlled.

One end of the cam shaft, outside of the crank casing, is provided with an eccentric 85. Two rods 86 and 87 are connected to this eccentric, one of which operates an oiling device 88. The other rod 87 is detachably connected to a rocker 89 which operates two pumps 90. These pumps are arranged to force gasoline and a lower grade fuel, such as kerosene or the like, from suitable tanks 35 into the separate compartments of a small vessel 91, which is mounted upon an elbow 92, the latter in turn being fixed to the body of a mixer or carburetor 93. The carburetor is centrally fixed to the manifold pipe 52.

40 Each compartment of the vessel 91 is provided with an inlet pipe 94 leading from the corresponding pump and an overflow pipe 95 leading back to the main supply tank. Two pipes 96 (see Fig. 1) lead from the compartment containing kerosene or other low grade fuel. These pipes (see Fig. 2) are connected to a hollow cap piece 97, which is secured to the head 2 of each cylinder over the exhaust valve. This cap can be removed to afford access to 45 the exhaust valve. At the same time, it is hollow and forms a heater for kerosene or other like low grade fuel, employed in the carburetor, the kerosene circulating therethrough from the vessel 91.

55 Either one of the compartments of the vessel 91 is connected by a three-way valve 98 to a fuel supply pipe 99, which opens through a contracted nozzle-like air-inlet 100 in one side of the mixing chamber of the carburetor 93. A supplemental air-inlet at the upper portion of the mixing chamber is controlled 60 by a valve 101, which is held to its seat by a spring 102. The stem 103 of this valve is provided with an adjustable abutment 104 which is arranged to engage a valve 105.

This valve is held to its seat by a spring 106, and is arranged to control a supply of water to the mixing chamber and which passes to the valve seat from a pipe 107. Needle valves 108 and 109 regulate the amount of liquid fuel and water passing into the mixing chamber. 70

The main air-inlet of the carburetor is controlled by a throttle valve 110, which is adapted to be manually operated by a 75 handle. A throttle valve 111 is arranged between the mixing chamber and the manifold pipe 52, which is connected to the inlet valve casings of the separate cylinders. This throttle valve may, if desired, be manually controlled, but is preferably automatically controlled by a governor. For this purpose, the shaft of this valve is provided with an arm 112 (see Fig. 3) which is arranged to be engaged by the lower end of a rock arm 113. 80 This arm is pivoted between its ends on a bracket 114 and its upper end is adjustably connected to a rod 115. The opposite end of the rod 115 is connected to a rock arm 116 mounted on one end of a shaft 117. This 85 shaft is journaled in brackets 118 on a crank casing and one end of the shaft is provided with arms 119 arranged to engage a collar 120 on a sleeve 121. This sleeve is mounted upon a vertical governor shaft 122, which 90 is journaled in a suitable bearing in one of the brackets 118, and is connected at its lower end by intermeshing worm gears 123 to one end of the cam shaft 31. The sleeve 121 on the governor shaft is connected to 95 rock arms 124 which are pivoted to lugs 125 on the under side of a casing 126. Weighted lever arms 127 within the casing are connected to the rock arms 124, and are normally drawn together by springs 127'. A 100 cross arm 128 mounted on the governor shaft, is arranged to engage the inner ends of springs 129, the outer ends of which engage lugs 130 on the upper face of the lower wall of the casing 126. These springs form 110 a yielding connection between the governor shaft and the casing 126 and the parts carried thereby. The piston of the throttle valve 111 is thus controlled through the medium of the governor by the varying 115 speed of and the load on the engine. The casing 126 protects the parts of the governor and is provided with a cover 131.

The crank casing is provided with cover sections 132 and 133. The latter is arched, 120 as shown, and is provided with a smaller swinging cover 134.

It is obvious that changes may be made in the details set forth without departure from the essentials of the invention as defined in the claims. 125

I claim as my invention:—

1. In a horizontal, internal combustion engine, the combination with side frame bars, of a crank casing fitted between said 130

bars and having flanges overlapping and secured to said bars, a cross-support extending between said bars, cylinders mounted in one end of said crank casing and loosely resting 5 on said cross support, pistons in said cylinders, and a crank shaft journaled in said casing and connected to said pistons, substantially as described.

2. In a four-cycle, internal combustion 10 engine, the combination of a crank casing, a cylinder mounted at one end of said crank casing, a crank shaft and a separate parallel cam shaft journaled in said casing, two-to-one gearing connecting said shafts, a piston 15 in said cylinder, a connecting rod coupled to said piston and to said crank shaft, said cylinder having inlet and exhaust valves at its head end, rocker arms pivotally mounted intermediate their ends, cams on said cam shaft 20 engaging the ends of said rocker arms, and valve actuating rods connected to the opposite ends of said rocker arms and said gearing, the cams and rocker arms being arranged within said casing, substantially as 25 described.

3. In a horizontal, internal combustion engine, the combination of a crank casing, a motor cylinder at one end of said casing, a crank shaft journaled in said casing, a piston 30 in said cylinder, a connecting rod coupled to said piston and to said crank shaft, said cylinder having inlet and exhaust valves, a cam shaft journaled in said casing and arranged between said crank shaft and 35 said cylinder and above said connecting rod,

rocker arms pivotally mounted intermediate their ends in said casing and arranged on opposite sides of said connecting rod, cams on said cam shaft for operatively engaging the ends of said rocker arms, valve actuating rods connected to the opposite ends of said rocker arms, and gearing arranged in said casing and connecting said crank shaft to said cam shaft.

4. In a horizontal internal combustion 45 engine, the combination of a crank casing having a central longitudinal rib, an engine shaft journaled on the sides and central rib of said crank casing and having cranks on opposite sides of said central rib, horizontal 50 cylinders mounted at the rear end of said crank casing, pistons in said cylinders, connecting rods coupled to said pistons and to the cranks of said shaft, a cam shaft journaled in the upper rear portion of said crank casing above the paths of movement of said connecting rods, rocker arms pivotally mounted intermediate their ends upon the sides and central rib of said crank casing, said arms being arranged in pairs on opposite sides of said connecting rods, cams on said cam shaft operatively engaging the upper ends of said rocker arms, said cylinders having inlet and exhaust valves and operating rods for said valves connected to 60 the lower ends of said rocker arms.

DAVID P. DAVIES.
